UNITED STATES PATENT OFFICE

2,664,737

LOCKING DEVICE

Neil O. Holmsten, New Rochelle, N. Y.

Application December 22, 1949, Serial No. 134,575

1 Claim. (Cl. 70—211)

1

This invention relates to latches for French windows and the like and more particularly to a lock for such latches to prevent unauthorized operation thereof.

An object is to provide a lock which may be made unitary with the latch for installation therewith.

Another object is to provide a combined window latch and lock of novel and improved construction and which is compact and dependable in operation and is neat and pleasing in appearance.

Various other objects and advantages will be apparent from the following description taken in connection with the accompanying drawings in which certain specific embodiments have been set forth for purposes of illustration.

In the drawings:

Fig. 1 is a front elevation of a lock embodying the invention, shown attached to a window frame;

Fig. 2 is a central vertical section through the device shown in Fig. 1.

Fig. 3 is a section taken on the line 3—3 of Fig. 2;

Fig. 4 is a rear elevation of the lock before attachment to the window frame;

Fig. 5 is a view similar to Fig. 4, but with the base plate removed;

Fig. 6 is a view similar to Fig. 5, but with the lock bolt removed;

Fig. 7 is a transverse section taken on the line 7—7 of Fig. 1;

Fig. 8 is a front elevation of a window latch illustrating another embodiment of the invention;

Fig. 9 is a central vertical section through the device shown in Fig. 8;

Fig. 10 is a section taken on the line 10—10 of Fig. 9;

Fig. 11 is a fragmentary view similar to Fig. 10 with the lock bolt removed;

Fig. 12 is a transverse section taken on the line 12—12 of Fig. 8; and

Fig. 13 is a longitudinal section through a latch illustrating another embodiment of the invention.

Referring to the drawings more in detail the window latch is shown in Figs. 1 to 7 as applied to a swinging French window having a sash 15 and panes 16 and closing against a frame comprising a vertical bar 17. The bar 17 carries a latch 20 pivoted to a flange 21 on the bar 17 to swing outwardly and having a finger 22 extending through an opening 23 in the bar 17 and en-

2

gaging the sash 15 to hold the same closed. The latch 20 includes a handle 24 which pulls outwardly from the bar to release the sash. A shoulder 25 on the finger forms a stop to limit the downward movement of the handle 24.

The lock includes a housing 29 having a base plate 30 with top and bottom flanges 31 and 32 attached to the bar 17 as by non-removable screws or rivets 33 and 34. The housing 30 carries a lock cylinder 35 of standard type to be actuated by a key, and rotatable when unlocked, in a barrel 36 which is fixed to the housing 29. The lock cylinder 35 carries a crank arm 37 at the inner end. The arm 37 carries a pin 40 which extends through a slot 41 in a tongue 42 of a sliding lock bolt 43 which is mounted to slide in a chamber 44 in the housing 29 and carries a plunger 45 which is adapted to abut against a shoulder 46 on the handle 24 to prevent movement thereof. The pin 40 extends into an arcuate slot 47 in a base plate 30 which extends over an arc of about 180° and is designed to take the thrust of the pin 40 when in locking position. The slot 47 is of a size to closely fit the pin 40 in locking position, but is somewhat larger in other positions to permit free movement of the pin therein.

In the above-described lock the bolt 43 is freely slidable in the housing 29 by rotation of the cylinder 35 effected by its key, but is locked against barrel 36 with the plunger 45 in advanced position against the shoulder 46 of the handle 24 when the key is removed. When in such locked position the pin 40 is supported in the arcuate slot 47 so that the thrust due to any force applied thereto by the handle 24 is taken directly by the back plate 38. Hence the lock is relieved of any strain due to attempts to release the latch.

Fig. 13 shows a pivoted stop 70 having an arm 71 projecting into a hole 72 in a sliding plate 73 which is actuated by a pin 74 eccentrically mounted on the cylinder of a lock 75 similar to that above described. In this form the stop is shifted into the path of the latch or retracted therefrom by the key operated lock 75.

In the embodiment of Figs. 8 to 12, the latch 50 is pivoted between flanges 51 of a housing 52 having end flanges 53 attached to the bar 17 as in Figs. 1 to 7. The housing 52 carries a lock barrel 54 in which a lock cylinder 55 rotates. The cylinder 55 carries a crank arm 56 having an eccentrically located pin 57 engaging a slot 60 in the flange 61 of a sliding lock bolt 62 which slides in a recess 63 in the housing 52. The bolt

62 is adapted to engage beneath a shoulder 64 in the latch 50 when extended and to release said latch when retracted. The thrust of the shoulder 64 in this case is taken directly by the bar 17. Hence the locking effect is not dependent upon the strength of the lock cylinder.

In this embodiment the bolt 62 is shifted by rotating the lock cylinder 55 by the usual key, but is locked in advanced position as shown in Fig. 9 upon removal of the key.

While specific embodiments have been shown, the invention may be applied to various uses as will be apparent to a person skilled in the art.

What is claimed is:

A locking device for a hinged casement window having a sash swinging outwardly and closing against a fixed frame, comprising a latch pivoted on the inside of said fixed frame having a latching finger extending through said frame to engage and latch said sash, a handle carrying said finger swinging inwardly from said frame and having a shoulder movable toward said frame, a lock having a bolt sliding along said

frame to engage said shoulder when extended to prevent actuation of said latch, said lock having a rotatable key actuated cylinder, a crank arm attached to said cylinder and a pin connecting said crank arm to actuate said bolt, said bolt sliding between said shoulder and said frame, said frame extending beneath said shoulder to take the thrust of the handle and prevent the possibility of shearing the bolt when the handle is forced toward latch releasing position.

NEIL O. HOLMSTEN.
